UNITED STATES PATENT OFFICE.

SEBASTIANO MAGNANO, OF LAWRENCE, MASSACHUSETTS, ASSIGNOR TO MAGNANO CORPORATION, OF LAWRENCE, MASSACHUSETTS, A CORPORATION OF MASSACHUSETTS.

FEED MAGAZINE.

Application filed April 10, 1924. Serial No. 705,648.

This invention relates to mechanism for picking off and delivering articles one by one in succession from a stack or magazine and more particularly to improved devices for moving the articles comprising the stack or which are disposed in series within the magazine toward the picking off or selecting devices in order to provide a continuous supply of the articles at the picking off point.

For purposes of illustration the invention is herein disclosed as embodied in a mechanism for picking off and delivering detached loom elements, for example, drop wires from a magazine or horizontal stack to the warp threads of a loom. When as in this mechanism the article to be fed is quite thin and the picking or selecting device engages the edge of the article to push it endwise from the stack or magazine, it is essential for accurate operation that the articles forming the stack all lie in planes substantially parallel to the path of movement of the picker device as any inclination to such path results in failure of the picker to engage the edge of the article.

The principal object of the present invention is to provide simple and dependable mechanism for pushing the articles comprising the stack forwardly toward the picking device without subjecting them to any force which would have a substantial tendency to swing them out of perpendicularity to their path of movement toward the picker. A further object is to provide means capable of simultaneously feeding forward a plurality of parallel stacks of articles toward corresponding picker devices, the feeding means comprising a common actuating element.

In the accompanying drawings a preferred embodiment of the invention is illustrated by way of example:

Fig. 1 is a side elevation, partly broken away, of a machine for delivering drop wires from a magazine or horizontal stack to the warp threads of a loom and embodying the present invention;

Fig. 2 is a fragmentary vertical section taken longitudinally through the delivery end of one of the stacks or magazines as viewed in Fig. 1;

Fig. 3 is an elevation, parts being omitted, from the right hand end of Fig. 1;

Fig. 4 is a fragmentary detail in side elevation of the improved follower devices comprised in the present invention;

Fig. 5 is a vertical section, parts being omitted, substantially on the line 5—5 of Fig. 1; and

Fig. 6 is a view similar to Fig. 4 but showing the follower devices in inoperative position to facilitate filling the magazine.

In the illustrated embodiment of the invention the drop wire feeding machine comprises spaced substantially parallel side frame members 1 and 2 connected at their outer or rear ends by a transverse bar 3 (Fig. 3) and at their forward ends by transverse bars or shafts 4, 5 and 6. The frame thus formed is supported upon wheels or rollers 7 and 8 adapted to move along guide rails 9, of which but one is shown, which are temporarily arranged above the sheet of warp threads to which the drop wires are to be applied. Such a sheet of threads is indicated diagrammatically in section at W, Fig. 2.

A main drive shaft 10 is journaled in bearings in the upper parts of the frame members 1 and 2 and may be rotated in any suitable manner, as for example by an electric motor, not shown, carried by the frame. This drive shaft 10 is provided at its opposite ends with cranks indicated generally at 11 in Fig. 1 connected by suitable connecting rods and slide bars indicated generally at 12 with a warp selecting mechanism indicated at 13. As the arrangement and operation of this warp selecting mechanism forms no part of the present invention, it is unnecessary to describe it in detail.

The space between the side members 1 and 2 of the frame provides for a plurality of parallel magazines for the drop wires. In the present instance four such magazines are provided, these magazines consisting respectively of elongate flat bars 14, 15, 16 and 17 together with the spaces above and to each side of the respective bars.

The several bars 14, 15, 16 and 17 respectively are supported at their rear or outer ends upon adjustable brackets 18 carried by the cross rail 3. At its forward end each of the bars is provided with a depending lug 19 secured to a bracket mounted upon the transverse connecting bar 6. The several magazine bars are thus supported in parallel relation and with their upper edges substantially horizontal.

The forward ends of the several magazine spaces are defined by a transverse vertical

plate 20 secured at its opposite edges to the frame members 1 and 2 respectively. This plate is provided with a vertical slot lying in the vertical plane of each of the magazines bars 14, 15, 16 and 17, and the plate is spaced from the forward ends of the respective magazine bars a distance substantially equal to the thickness of one of the drop wires 21 which is to be fed to the warp threads. As herein illustrated these drop wires are of hairpin type so that they may be straddled over the magazine bars and held in proper relation by engagement of their depending legs with the sides of the bars. Obviously, if other types of drop wires were to be employed the magazines might be constructed otherwise than as herein shown but without in any manner departing from the present invention. As shown in Figs. 1 and 2, the drop wires are arranged in compact series upon the several magazine bars to form horizontal stacks 21^a, the forward wire in each stack engaging the rear surface of the plate 20.

25 A picker finger 22 is arranged to slide vertically in each of the vertical slots in the plate 20. Each picker finger projects beyond the rear face of the plate 20 a distance substantially equal to or slightly less than the thickness of one of the drop wires. Each picker finger is carried by a bracket 23 guided to slide vertically and each bracket is connected by a rod 24 to a crank carried by a transverse shaft receiving its motion from the drive shaft 10 through a train of gears indicated generally at 25. The several cranks operating the picker fingers 22 are disposed at substantially 90° apart so that the picker fingers are moved in succession.

40 In Fig. 2 one of the forward drop wires is shown as beginning its downward movement and when the picker finger 22 has nearly reached the lower limit of its movement the projecting lower end of the drop wire is caught between two constantly rotating rolls 27 and 28 and is thereby fed down until its legs engage a separator device 29 which spreads them to permit them properly to straddle over the warp thread which has been selected and is held in proper position by the mechanism 13. A temporary support 30 is provided for receiving the weight of the drop wire as the latter is delivered by rolls 27 and 28 to prevent breaking the thread.

45 The mechanism constituting the present invention is designed to push the series of drop wires constituting each stack 21^a bodily toward the plate 20 at the delivery end of the machine to provide a constant supply for the picker 22 to act upon. This feeding mechanism comprises a pair of vertically spaced guides 32 and 33 supported at their rear ends in a bracket 31 carried by the cross rail 3 and at their forward ends in a suit-

able bracket not shown supported by the side members 1 and 2. These guides are preferably arranged between the middle magazines, that is to say between the vertical planes of the supporting bars 15 and 16. A 70 sliding support 34 is mounted upon the guides 32 and 33 to slide toward and from the delivery end of the magazines. This support 34 is provided with an internally screw-threaded bore substantially parallel to 75 but intermediate the guides 32 and 33 for the reception of a threaded shaft 35. This shaft is journaled at its rear end in the bracket 31 and at its forward end in the bracket which supports the forward ends of 80 the guides 32 and 33.

The rear end of the shaft 35 is furnished with a bevel gear 36 meshing with a bevel gear 37 carried by a transverse shaft 38 journaled in suitable bearings carried by 85 the frame. A ratchet wheel 39 is secured to the shaft 38 and a lever arm 40 is mounted to turn freely upon said shaft. This lever arm carries a driving pawl 41 engageable with the teeth of the ratchet 39 90 and is rocked by means of a connecting rod 42 whose opposite end is secured to a crank 43 carried by a shaft 44 which is rotated by the gear train 25. The arrangement is such that as each drop wire is fed downwardly, the ratchet wheel 39 is moved forward one tooth. Preferably a pinion 45 is also secured to the shaft 38 and this pinion meshes with a gear 46 provided with a hand crank 47 which is useful in turning the 100 shaft 38 reversely before loading the magazines.

The sliding support 34 is provided with an upstanding bracket 48 to which a fixed transversely extending shaft 49 is secured. 105 This shaft extends across the entire series of magazines and supports bell crank levers 50, one for each magazine, said bell crank levers being disposed substantially in the vertical planes of the respective drop wire 110 supporting bars 14, 15, 16 and 17. Each of the magazines is furnished with a follower plate 51 adapted to engage the rearmost drop wire in the magazine. These follower plates are of substantially the same width 115 as the drop wires and vertically elongate. Their lower ends as indicated at 51^a are preferably bifurcated to straddle over the upper edges of the corresponding magazine bars. Each follower plate is provided with 120 a rearwardly extending boss 52 substantially midway its length and this boss is secured by a pivot pin 53 to the lower free extremity of the corresponding lever 50. The other arm 54 of each of the bell crank levers 125 50 is provided with an opening in which one end of a spring 55 is secured. The opposite ends of the several springs are connected at the points 57 to brackets 58 carried by the support 34. The tendency of 130

these springs is to swing the lever arms 50 in a clockwise direction as viewed in Fig. 4 so as to press the several follower plates firmly against the rearmost drop wire of the 5 respective stacks.

The support 34 is also provided with a transverse retaining bar 59 disposed in a horizontal plane below that of the shaft 49 and in a position such that the upper ends 10 of the several follower plates 51 may be snapped beneath it as shown in Fig. 6 to render them inoperative if desired.

In the operation of the machine the screw-threaded shaft 35 is turned intermittently 15 by the pawl and ratchet mechanism described, thus slowly feeding the support 34 toward the delivery end of the machine.

The slight variation in thickness which may occur in the drop wires is compensated for by 20 the yielding character of the follower plates 51, while the variation in thickness from top to bottom of the drop wires is cared for by the free pivotal movement of the follower plates about their points of connection with 25 the levers 50. The follower plates thus bear with a uniform pressure upon an extended surface of the rearmost drop wires so that the force acting to move the stacks bodily toward the delivery end of the machine is 30 in a direction substantially parallel to the upper edges of the several magazine plates

14, 15, 16 and 17 respectively with the result that the forward drop wire is at all times maintained in close engagement with the 35 inner surface of the plate 20 so that the picker finger 22 may certainly engage the upper edge of the drop wire for feeding it downwardly.

When the drop wires in any particular 40 stack need replenishing the crank 47 is manipulated, after disengagement of the pawl 41 from the ratchet wheel 39, to impart movement to the shaft 35, thereby carrying the support 34 toward the rear end 45 of the machine. While loading a new supply of drop wires into the magazines the follower plates 51 may be swung rearwardly and permitted to snap up behind the retainer bar 59 to prevent them from interfering with the drop wires as they are 50 placed upon the magazine bars. When the magazines have been filled the follower plates are disengaged from the bar 59 and immediately assume operative position, 55 acting against the stacks of drop wires with resilient pressure.

I claim:

1. In a machine of the class described a 60 magazine for holding a stack of articles arranged in series, and means for urging the stack toward one end of the magazine comprising a sliding support, a guide for the support, means for moving the support along the guide, a lever mounted on the support, a follower plate pivotally supported

by the lever for engaging the endmost article in the magazine, and yieldable means tending to swing the lever to hold the follower against such endmost article.

2. In a machine of the class described 70 an elongate magazine for holding a stack of articles arranged in series, a sliding support movable lengthwise of the magazine, spaced guides for the support, the support having a threaded bore, a rotary screw 75 threaded shaft engaging the bore in the support for positively moving the support, a lever pivotally mounted upon the support, a follower carried by the lever, and a spring for resiliently urging the follower into 80 engagement with the endmost article in the magazine.

3. In a machine of the class described an elongate magazine for holding a series of articles, a sliding support movable lengthwise of the magazine, a screw-threaded shaft cooperating with the support positively to move the latter toward the delivery end of the magazine, a shaft carried by the support, a lever pivoted upon the shaft, a follower plate pivotally secured to the end of the lever, and a spring connected at its opposite ends to the lever and support respectively tending to press the follower plate 90 into contact with the endmost article of the 95 series.

4. In a machine of the class described an elongate magazine, a support arranged to slide lengthwise of the magazine, a screw-threaded shaft having threaded engagement 100 with the support to move the latter positively toward the delivery end of the magazine, a bell-crank lever pivoted upon the support, an elongate follower plate pivoted at a point substantially midway its length 105 to one arm of the bell-crank lever, and a spring connecting the other arm of the bell-crank lever with the support.

5. In a machine of the class described a 110 magazine comprising an elongate bar for supporting a series of articles, a pair of spaced guides extending substantially parallel to said bar, a support sliding on the guides, means for positively moving the support, a lever fulcrumed on the support, 115 a follower plate pivotally secured to the free end of the lever, and a spring normally urging the follower plate toward the delivery end of the magazine.

6. In a machine of the class described a 120 plurality of parallel elongate magazines, a support guided to move in a plane substantially parallel to said magazine, a shaft carried by the support extending transversely 125 of the magazines, a lever pivoted upon the shaft, one for each magazine, a follower plate within each magazine, means pivotally connecting each plate to one of said levers, and independent springs tending to turn the several levers to press their respective fol- 130

- lower plates against the contents of the several magazines.
7. In a machine of the class described a plurality of parallel magazines each comprising an elongated bar for supporting a series of articles, a pair of guides disposed between a pair of adjacent magazines, a support sliding on said guides, a rotary shaft having screw-threaded engagement with the support for positively moving the latter longitudinally of the magazines, a shaft carried by the support extending transversely across the several magazines, levers independently pivoted upon said shaft, one lever depending into each magazine substantially in the plane of its elongate supporting bar, an elongate follower plate pivotally secured at a point substantially midway its length to the free extremity of each lever, and a spring tending to move each follower plate toward the delivery end of its respective magazines.
8. In a machine of the class described an elongate magazine, a support movable longitudinally of the magazine, a lever pivotally secured to the support, a follower plate arranged within the magazine and pivotally connected to the end of the lever, a spring urging the plate toward the delivery end of the magazine, and means for temporarily restoring the plate from moving under the action of the spring.
9. In a machine of the class described a magazine for holding a series of articles, a support movable longitudinally of the magazine, a lever carried by the support, a follower plate pivotally secured to the lever, a spring tending to move the follower plate into contact with the endmost article of the series, and a transverse bar carried by the support with which the follower plate may be engaged to retain the plate in inoperative position during the filling of the magazine.

Signed by me at Lawrence, Massachusetts, 45
this 29th day of March, 1924.

SEBASTIANO MAGNANO.
